UNITED STATES PATENT OFFICE.

ALBE F. HYDE, OF BOSTON, MASSACHUSETTS.

CHUCK.

SPECIFICATION forming part of Letters Patent No. 239,047, dated March 22, 1881.

Application filed November 1, 1880. (No model.)

To all whom it may concern:

Be it known that I, ALBE F. HYDE, a citizen of the United States, residing at Boston, in the county of Suffolk and State of Massachusetts, have invented certain new and useful Improvements in Chucks for Centering-Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to improvements in chucks for centering-machines for the purpose of securing shaftings firmly and in a concentric position to the usual revolving centering-drill, by means of which a central recess is made in the end of the shaft; and this improved chuck consists of a stationary cylindrical case, in combination with an internal movable ring having jointed links hinged to clamping-jaws that are movable on fulcra secured to the stationary case, the said internal ring being operated preferably by means of a screw-shaft located in stationary bearings and working within a laterally-adjustable rack, the teeth of which engage into teeth on the exterior surface of the internally-movable ring in a manner as will hereinafter be more fully shown and described, reference being had to the accompanying drawings, in which—

Figure 1 represents a sectional side elevation; and Fig. 2 represents a cross-section on the line A B, shown in Fig. 1.

Similar letters refer to similar parts wherever they occur on the different parts of the drawings.

40 a a represent the cylindrical stationary case, having central perforations, a' a', through which the shaft to be centered is inserted.

b is the movable ring, properly turned, so as to fit nicely within the cylindrical case a, in 45 which it can be turned around its axis by

means of the screw-shaft c, having screw-threaded end c' working within the laterally-adjustable rack d, the teeth d' of which engage into the teeth b', that are made on a portion of the periphery of the said movable ring 50 b, as shown.

e e e are the clamping-jaws, movable on the stationary fulcra f f f, and jointed in their outer ends to the ring b by means of the links g g g, as shown. The links g g g may be dispensed with and the outer ends of the clamping-jaws e e e jointed directly to the interior of the ring b, although I prefer in practice to use the said links, as shown in the drawings.

To secure a shaft between the clamping-jaws 60 of the chuck it is only necessary to turn the screw-shaft c, by means of a suitable handle or crank, c'', around its axis until the rack d and the ring b, with its clamping-jaws e e e, are moved to the positions shown in dotted lines in Fig. 1, 65 when the shaft is inserted between the clamping-jaws e e e, and the ring b turned around its axis in an opposite direction by means of the screw c' and rack d until the jaws e e e firmly grasp and hold the shaft between them, 70 when the operation of centering the end of the shaft is performed by the usual means.

It will be seen by full lines in Fig. 1 that the jaws e e e may be moved into such a position as to secure shaftings or wires of very small 75 diameters, if so desired.

Having thus fully described the nature, construction, and operation of my invention, I wish to secure by Letters Patent, and claim—

In combination with the case a, ring b b', 80 links g g g, and clamping-jaws e e e, the screw-threaded rack d d' and screw-shaft c c', as and for the purpose specified.

In testimony whereof I have affixed my signature in presence of two witnesses.

ALBE F. HYDE.

Witnesses:

ALBAN ANDRÉN,
HENRY CHADBOURN.
